JULIAN S. BROWN, OF SYRACUSE, NEW YORK.

INTERNAL-COMBUSTION ENGINE.

1,088,259.

Specification of Letters Patent.

Patented Feb. 24, 1914.

Application filed June 19, 1911. Serial No. 634,018.

To all whom it may concern:

Be it known that I, JULIAN S. BROWN, of Syracuse, in the county of Onondaga and State of New York, have invented a certain 5 new and useful Internal-Combustion Engine, of which the following is a specification.

My invention has for its object the production of a particularly simple and efficient 10 valve arrangement for internal combustion engines; and it consists in the combinations and constructions hereinafter set forth and claimed.

In describing this invention reference is 15 had to the accompanying drawing which is a vertical sectional view of one embodiment of my invention.

As will be understood by those skilled in the art, the intake valve of internal combustion 20 engines is adequately cooled by the incoming motive fluid and does not depend entirely on the cooling medium as water or air; and the heat from the exhaust valve and its seat is conducted through contiguous parts 25 cooled by the cooling medium; and in order to efficiently cool the exhaust valve, such valve should coat with a seat formed directly on an inner wall of the cylinder in contradistinction to a removable seat as a 30 cage detachable from the cylinder.

In the present internal combustion engines, either both inlet and exhaust valves are supported by detachable cages in order that said valves may be easily removed, or 35 both valves are arranged directly in openings formed in the cylinder and coat with seating surfaces integral with the cylinder in order that the exhaust valve will receive full benefit of the cooling medium.

40 In locating the inlet and exhaust valves directly in openings in the cylinder, such valves have not been easily removable and replaceable as in order to remove the same it has been necessary to remove the cylinder 45 from the crank case or remove the head of the cylinder in case the head is removable.

By my invention the exhaust valve is located in an opening formed in, and coacts with a seat formed directly on, the end wall 50 or head of the cylinder and is removable through an additional opening in the head of the cylinder, without removing the cylinder from the crank case or removing the head of the cylinder and parts carried thereby.

55 My invention comprises, generally, a cylinder formed with an opening in the end

wall or head thereof and with a valve seat at the inner end of the opening, an inwardly opening exhaust valve having a head coacting with said seat, the cylinder also having a second opening of greater diameter than the head of the valve whereby the valve is removable and replaceable through the second opening, and a removable inlet valve and valve seat closing the second opening. 60 The inlet and exhaust valves open inwardly in the same general direction lengthwise of the cylinder, and in the illustrated embodiment of my invention said valves are arranged with their axes parallel to the axis 65 of the cylinder, but obviously may be arranged at an angle to each other as in a cylinder having a dome-shaped head.

1 is the cylinder provided with integral side and end walls and having an opening 2 70 in its end wall or head and a valve seat 3 at the inner end of the opening, the opening 2 communicating with the exhaust passage 4.

5 is an inwardly opening exhaust valve having its head coacting with the seat 3 and 80 its stem 6 extending axially of the opening 2 and through a guide 7 for said stem, said guide being attached to the head of the cylinder in any suitable manner. The head and the stem of the exhaust valve are of less combined length in a direction lengthwise of their axis than the maximum distance between the inner face of the end wall or head of the cylinder and the opposing face of the piston of the engine, and thus the valve may 85 be moved, as a whole, axially into the piston chamber and then shifted laterally in said chamber. The cylinder is also formed with an opening 8 in the head thereof, the opening being of greater diameter than the opening 2 and the exhaust valve. 9 is a removable valve seat as a cage arranged in said opening 8 and secured to the cylinder by any suitable means. The cage is formed with a seating surface 10 at its inner end and the 90 passage of said cage communicates with the inlet conduit 11 for the motive fluid.

12 is an inwardly opening inlet valve having its head coacting with the seat 10 and its stem 13 extending upwardly through a guide 105 14 supported by the outer end of the cage, said guide being usually formed integral with the cage.

The valves 5 and 12 are held against their seats respectively by springs 16 and 17 interposed between detachable shoulders 18 and 19 on their stems 6 and 13, and the

guides 7 and 14, the spring 16 holding the guide 7 in position. The valves may be operated in any suitable manner as by rock arms 20 and 21, and the valve stems 6 and 5 13 are separable from the shoulders 18 and 19 and the rock arms 20 and 21.

The cage 9 is held in position by a plug 15 threading in the upper end of the opening 8, and having a central non-circular 10 opening for receiving a tool or wrench.

The valves 5 and 12 are preferably interchangeable that is, of the same size, and in placing the valves in position after the cylinder has been mounted on the crank case, the 15 exhaust valve is first passed through the opening 8 and moved laterally over opposite to the opening 2, or in such position relatively to such opening, that the stem 6 of such valve can be engaged by the hand or a 20 suitable tool, and the valve is then drawn up against its seat 3 and the guide 7, and the other parts placed in position. The cage 9 with the valve 12 and parts assembled therein is then secured in position in the opening 25 8. In removing the valves the reverse of such operation takes place, it being of course necessary to turn the crank shaft of the engine until the piston is near the end of its out stroke.

30 Although I have shown but one valve removable through an enlarged opening in the cylinder, as the opening for the valve cage, obviously if the cylinder is provided with additional valves they may be removable 35 through such opening.

What I claim is:

40 1. In an internal combustion engine, a cylinder including an end wall integral with the side walls of the cylinder and having an opening therethrough extending in a direction substantially parallel to the axis of the cylinder, an inwardly opening exhaust valve seating directly on the end wall at the inner 45 end of the opening, and non-removable through the opening, said end wall having a second opening located at one side of, and substantially corresponding with, the first opening but of a diameter sufficient to permit of the removal therethrough of the exhaust valve, a removable casing mounted in the second opening, and a valve substantially corresponding to the exhaust valve seating upon the casing and removable there-

55 with through the second opening, the exhaust valve, as a whole, being of less length in a direction lengthwise of its axis than the maximum distance between the inner face of said end wall and the opposing face of the piston of the engine and being movable inwardly from its seat into the piston chamber, then laterally in the piston chamber into registration with the second opening, and finally outwardly from said chamber through the second opening when the casing is removed, substantially as and for the purpose described.

60 2. In an internal combustion engine, a cylinder including an end wall integral with the side walls of the cylinder and having an opening therethrough extending in a direction substantially parallel to the axis of the cylinder, a removable casing mounted in the opening, an inlet valve seating on the casing and removable therewith from the cylinder, a second opening in the end wall located to 70 one side of, and extending substantially parallel with, the first opening, and of less diameter than the same, an exhaust valve having a head seating directly on the end wall at the inner end of the second opening, and 75 non-removable therethrough from the cylinder, and of less diameter than the first opening, said valve being provided with a stem, the valve head and the stem being of less combined length in a direction lengthwise 80 of their axis than the maximum distance between the inner face of said end wall and the opposing face of the piston of the engine, whereby the valve may be moved axially into the piston chamber, then laterally in the chamber for alining the valve with the first-named opening and finally 85 axially in the reverse direction through the first-named opening after the removal of the casing therefrom, substantially as and for 90 the purpose specified.

95 In testimony whereof, I have hereunto signed my name in the presence of two attesting witnesses, at Syracuse, in the county of Onondaga, in the State of New York, this 100 15th day of June, 1911.

JULIAN S. BROWN.
